UNITED STATES PATENT OFFICE

JACOB C. HEIM, OF PHILADELPHIA, PENNSYLVANIA, ASSIGNOR TO BROWN & BAILEY COMPANY, A CORPORATION OF PENNSYLVANIA

FOLDABLE BOX

Application filed July 13, 1928. Serial No. 292,530.

My invention relates to foldable boxes, a principal object being to provide a foldable box which may be constructed from a unitary blank of suitable material, the blank being cut out by a suitable die and the different parts thereof then folded into and secured in proper relation to form the completed box. In my improved box double end closures are provided, each of which comprises wing members which are inserted within the box and, due to their design, inter-engagement and inherent resiliency, form efficient seals for the contents of the box and are not subject to dislodgement in ordinary handling. Furthermore, due to the double end closures and the sturdy construction of my box relatively heavy materials and merchandise may be safely packed therein.

My invention includes all of the other various objects and novel features of design, construction and arrangement hereinafter more definitely specified or described or which will be apparent from the accompanying drawings in which I have illustrated one embodiment of my invention.

In said drawings, in which the same numerals designate like parts in the different figures, Fig. 1 is a plan view of the blank before the same is folded up to form the box, the points at which the blank is scored or weakened to facilitate the folding operation being indicated in dot and dash lines and the points at which the blank is cut entirely through being indicated in full lines; Fig. 2 is a section on the lines 2—2 of Fig. 4; Fig. 3 is a section on the lines 3—3 of Fig. 4; Fig. 4 is a top plan view, partly broken away, of the folded box and Fig. 5 is a longitudinal fragmentary section showing the position of the end closures at the initial step of their closing.

The blank may, preferably, be cut from heavy cardboard, paper stock or other suitable material having inherent resiliency, by a die at a single operation, the preferred form of blank being shown in Fig. 1 in which the bottom of the box is shown at 1, the top at 2, one side at 3 and the other side at 4 which is adapted to be secured by staples 5, or stitches, adhesives or other suitable means to the lateral extension 6 of the bottom 1. End mem-

bers 7, 7 extend from each end of the bottom 1 and are provided with wing members 8 and from each end of the top 2 extend end members 9, 9 provided with wing members 10. The material of the blank at each end thereof 55 between the adjacent closure panels 7 and 9 is divided to form a pair of the wing members 8 and 10. The wing members 8 and 10 are provided with curved edge portions 11 which facilitate the insertion, guiding and 60 closing of the end closures.

In forming the box from the blank, that part of the blank comprising the side 3, top 2 (and end members 9 with wing members 10) and side 4 is folded about the score 12 into a 65 position at right angles to the bottom 1; the top 2 is then folded about the score 13 into a plane parallel with the bottom 1, following which the side 4 is folded downwardly about the score 14 into a plane parallel with side 3 70 and secured by staples 5 to the flap 6 which has been folded upwardly about the score 15 into parallel relation with the side 3, thus forming the tubular, rectangular body portion of the box.

In closing the ends of the box the wing members 8 of the end members 7, 7 are folded upwardly about the scores 16 into positions substantially at right angles to the end 7, 7 and the curved edge portions 11 of the wings 8 are first fed into the open ends of the box, the ends 7, 7 being slightly folded about the scores 18 to permit the insertion of the curved portions 11 within the open ends as shown in Fig. 5. The folding of the ends 7, 7 about the scores 18 is then proceeded with and the wing members 8 are progressively fed into the interior of the box until the ends 7 have been brought into closure position as shown in Fig. 4. The end members 9, 9 with the wing members 10 are then in like manner folded about the scores 19 and 20 into closure position, the ends 9, 9 lying against the outer face of the adjacent end 7 and the wings 10 telescoping 95 between the adjacent wings 8 and the adjacent sides. The ends 7 and 9 and the wing members 8 and 10 preferably correspond to the depth of the box so that in closed position they fit tightly therein. Due to the inherent resiliency of the cardboard or other material 100

of which the box is formed, the wing members will tend to return to positions in the plane of the end members of which they form extensions so that in addition to the retention of the end closures provided by the frictional engagement between the parts, I obtain further security of closure by reason of the spring tension exerted by the wing members 10 against the adjacent sides, supplemented by 15 the spring tension exerted by the wing members 8 against the adjacent wing member 10.

In opening the box, the exterior end closures 9 may be readily withdrawn from closure position by grasping the exposed edges 21 with the fingers. Inasmuch as, when closed, the corresponding edges of the inner end closures 7 are positioned within the box, I provide apertures 22 within the panels of the inner end closures within which a finger 20 may be inserted to assist in their withdrawal.

It will now be seen that by my invention I have provided an improved box having double end closures which are securely retained against accidental opening; which 25 provide effective seals against the sifting out of contents of a granular or powdery nature; which may be readily opened and closed without mutilation of the box, thus permitting its repeated refilling with goods and merchandise; and a box which may be folded from a blank with facility.

While I have herein described and illustrated with considerable particularity one embodiment of my invention, I do not thereby 35 desire or intend to in any manner limit myself specifically thereto as the design, construction and arrangement of the various parts may be modified if desired from the precise form to which I have referred without departing from the spirit and scope of the 40 invention as defined in the appended claims.

Having thus described my invention, I claim and desire to protect by Letters Patent of the United States:

45 1. A box formed from a unitary blank of foldable material comprising a top, a bottom, sides, means for securing one of said sides to said bottom, and double closures for each end of the box, each closure comprising a panel, 50 foldable resilient wing members on each panel adapted to be inserted within said box, the material of the blank at each end thereof being divided between the adjacent closure panels to form a pair of the said wing 55 members.

60 2. A box formed from a unitary blank of foldable material comprising a top, a bottom, sides, a lateral extension from the bottom, means for securing one of said sides to said lateral extension, and double closures for each end of the box, the outer of said closures forming a foldable extension of said top, the inner of said closures forming a foldable extension of said bottom, each of said closures 65 comprising a panel and wing members on each

panel adapted to be inserted within said box, the panels of said inner closures when closed being located within the box and provided with apertures within which a finger may be inserted to assist in the withdrawal of said 70 inner end closures.

In witness whereof I have hereunto set my hand this 11th day of July, 1928.

JACOB C. HEIM.
